UNITED STATES PATENT OFFICE.

WILLIAM H. S. MOORE, OF CLEVELAND, OHIO.

OIL-WELL UNDERREAMER.

Application filed May 31, 1922. Serial No. 564,791.

My invention relates in general to tools for drilling wells, such as oil, gas, and artesian, and more particularly to underreamers. In drilling wells, the cutting tools must pass through the pipe forming the well casing, and with the solid bits in general use the hole can not be made larger than the inside diameter of the casing. In 5 order that the casing may be easily driven downwardly, the hole must be enlarged in advance of the casing to a size somewhat larger than the outside diameter of the usual driving shoe on the end of the casing, and the couplings connecting the sections of casing. This is accomplished by a tool known 10 as an underreamer. The cutters or bits of this tool must be so mounted that the underreamer may pass freely downwardly or upwardly through the casing, and when below the end of the casing will expand automatically so that in working they will 15 enlarge the hole to a diameter of the requisite size relatively to that of the casing.

An object of the invention is to provide 20 an underreamer in which the cutters or bits are securely housed, can not become detached, or fall into the hole if broken, and in which the bits can not snag or bind in the casing while being inserted or withdrawn.

The manner of connecting cutters to the body of the reamer has heretofore been a 25 weak point in such tools. In most of the tools heretofore used the cutters have been on a saddle which slides up and down in the body and held in position by a spring which carries the entire weight of the cutters. The connection between the cutters and the saddle has been a point of weakness and cutters 30 frequently break at this point, letting about 90% of the cutters drop in the hole. Such cutters are exceedingly difficult to fish out of the hole, and holes have often been abandoned for the reason that it was impossible to fish out the cutter.

It is an object of the present invention to 35 provide a tool in which the cutters have greater strength and durability for the reason that the bits in operating position are in solid contact with substantial portions of the body and receive the impact in such manner that they are capable of withstanding great 40 shocks and strains incident to the blows delivered in drilling.

A further object of the invention is to 45 provide improved means for expanding and col-

lapsing the cutters, which positively prevents the cutters from becoming "cocked", i. e., one set while the other is wholly or partly collapsed, either in working position or during insertion or withdrawal of the tool.

A further object is to provide an expanding and collapsing means for the cutters which insures positive setting of both cutting bits automatically when the tool comes to working position beneath the end of the casing, and in which the tools are rigidly held in extended position while operating.

A further object is to provide a tool in which the cutters are free to move to a position entirely within the body while in the well casing during the insertion or withdrawal of the tool.

In reamers heretofore used much trouble has been caused by the failure of the cutter 75 collapsing mechanism to operate properly when the tool is withdrawn from operative position into the casing. This is caused by the driving shoe at the lower end of the casing getting out of round, and as this is depended upon to collapse the cutters as the reamer is withdrawn, only one cutter will engage the shoe and be drawn down to the collapsing point, while the other cutter remains in expanded position or nearly so, and wedges in the casing. In such cases the entire casing has to be "pulled" in order to remove the tool.

It is an object of the present invention to overcome the above mentioned difficulty by 80 providing a plurality of trips separate from the cutters for controlling the cutter locking and releasing means, the trips being operable upon being raised into engagement with the casing to release the cutters, actuation of one of the trips being sufficient to release all the cutters so that in the event the driving shoe gets out of round there is no danger of failure of the cutter collapsing devices.

A further object of the invention is to 85 provide a cutter controlling mechanism which will enable the tool to be withdrawn from the casing and cutters removed therefrom and replaced without the necessity for resetting the tool before it is reinserted in the casing.

A further object is to provide a tool in 90 which the cutter setting spring operates upon a locking device separate from the cut-

ters, and has not direct connection with the cutters, whereby the spring can be made much lighter and is not subjected to heavy loads in use. This enables the cutters to be easily set in operative position or collapsed.

A further object is to provide a tool which has positive guiding means which prevents it from working out of alignment with the casing.

10 Other objects will be apparent from the following description and the annexed drawings.

15 The following description and accompanying drawings set forth in detail certain means embodying my invention, the disclosed means, however, constituting but one of the various mechanical forms in which the principle of the invention may be applied.

20 In said annexed drawings, Fig. 1 is a longitudinal axial section taken through the cutter releasing trips, Fig. 2 is a longitudinal axial section taken at right angles to the section shown in Fig. 1, and showing the cutters in expanded position. Fig. 3 is a section similar to Fig. 2 showing the cutters in collapsed position; Fig. 4 is a fragmentary section similar to Fig. 1 showing the trips in retracted position. Fig. 5 is a perspective view of a cutter; Fig. 6 is a side elevation of the tool looking toward one of the cutters; Fig. 7 is a side elevation of the tool looking toward one of the trips, a portion being broken away 35 to show part of the trip mechanism; Fig. 8 is a section on line 8—8 of Fig. 1; Fig. 9 is a section on line 9—9 of Fig. 4; Fig. 10 is a section on line 10—10 of Fig. 2.

40 Referring to the annexed drawings, the tool has a main body portion 1 in which the cutters and cutter actuating mechanism are mounted. The body portion 1 is circular in cross section, and has a stepped upper end consisting of a reduced threaded portion 2 and still further reduced extension 3 above the threaded portion 2, and a threaded nipple 4 at the end of the reduced portion 3. At its lower end the body member 1 has a threaded nipple 5 to which may be attached 45 either a pilot member or a tool holder. A connecting member 6 is attached to the upper end of the body member 1, said member having a threaded socket 7, whereby it can be screwed upon the end nipple 4 of the body member. The connecting member 6 has a threaded nipple 8 at its upper end, by means of which it may be connected to the actuating rod. The connecting member 6 has an axial bore 9 extending from its upper 50 end to a counter bore 10 at the lower end thereof. The body member 1 has an axial bore 11 of the same diameter at the counter bore 10 in the connecting member 6.

60 Adjacent its lower end the body member 65 1 has a slot 12 diametrically therethrough

to receive the cutters. At the upper end of the slot 12 upwardly extending channels 13 are provided on opposite sides of the body to receive the shanks of the cutting tools. Each of the channels 13 has a recess 14 in the bottom thereof at its upper end. The cutters 15 each have a shank 16 narrower than the head and fitting in the grooves 13 of the body. The shank 16 of each of the tools has an inner projection 17 at its upper end 70 adapted to fit in the recess 14 at the upper end of the groove 13, and a rabbet 18 at its outer upper edge. The heads of the cutters 15 fit within the slot 12 in the body 1 and have pivotal movement about their upper ends whereby the heads of the cutters may be swung out to project the required distance from the outer face of the tool. In the slot 12 beneath the cutters 15 is mounted a follower 19 which is slidably mounted upon an axial pin 20 rigidly secured to a plug 21 fixed within the bore 11 adjacent the lower end of the body member 1. The follower 19 has a tubular boss 22 slidably fitting within the bore 11 and end flanges 23 80 which are flush with the outer surface of the body member 1. A light coil spring 24 within the boss 22 and interposed between the plug 21 and the follower 19 serves to normally hold the follower 19 in engagement 85 with the under faces of the cutters 15. The follower 19 has an upper face 25 which has a slight incline downwardly from the center to the ends thereof so that the follower is readily forced down when the cutters 15 are moved to collapsed position. The follower 19 also serves to prevent the cutters from falling into the hole should the cutter be broken or torn loose from the body member, and also to prevent entrance of 90 rock, splinters, mud, or other foreign matter within the body.

95 At the upper end of the cutter receiving slot 12 the body 1 is provided with a central rectangular recess 26 in which is slidably mounted a wedge block 27 which serves to force the cutters 15 outwardly into cutting position, and to rigidly hold the cutters in such position. The lower end of the wedge block 27 is pointed so that as the block 100 is forced downwardly the cutters 15 are spread apart and forced into working position. The body portion of the block 27, however, has parallel side walls against which the inner faces of the cutters 15 abut 110 when in working position so that impacts on the tool do not tend to dislodge the block 27 and the cutters 15 are rigidly held in working position.

115 Mounted within the wedge block 27 is a roller 28 which has a peripheral groove adjacent each end. The block 27 is provided with vertical apertures 29 leading to the grooves at the ends of the roller 28 on opposite sides of the roller.

Adjacent its upper end the body member 1 is provided with a rectangular slot extending diametrically therethrough, in which is mounted a pulley block 30. The pulley block 30 has a central bore 31 of the same diameter as the bore 9 in the member 6. The block 30 is provided with recesses 32 on opposite sides of the central bore 31, in each of which are mounted a double sheave 33.

A cable 34 passes over the sheave 33 at one side of the center, extends downwardly through the axial bore 11 of the body member, is threaded through the apertures 29 and over one end of the grooved roller 28, extends upwardly within the axial bore 11, and is passed over the sheave 33 at the same side of the center of the block. A second cable 35 is passed over the sheave 33 on the opposite side and the roller 28 in the wedge block 27 in exactly the same manner. The ends of the cables 34 and 35 are connected to slides 36 which are mounted in diametrically opposed grooves 37 in the body member 1. A rod 38 is rigidly connected to the wedge block 27 at its lower end, extends upwardly through the sheave block 30, and has its upper end slidably fitting in the bore 9 of the connecting member 6. The rod 38 has a fixed collar 39 which seats upon the top of the sheave block 30 when the wedge block 27 is in its lowermost position. A coil spring 40 is interposed between the fixed collar 39 and the shoulder at the upper end 25 of the counter bore 10 in the connecting member 6.

The spring 40 serves to normally hold the wedge block 27 in its lowermost position in which position the cutters 15 are held in working position. In the grooves 37 of the body member 1 beneath the slides 36 therein are mounted slides 41 in the form of narrow elongated strips fitting in said groove. Each slide 41 has an inturned upper flange 42 which sets against the bottom of the groove, a trip receiving slot 43 in its outer wall, an inwardly projecting rib 44 beneath the slot 43 corresponding in height to the flange 42 and engaging the bottom of the groove 37, and a downwardly projecting portion which fits in a shallower groove 45 forming a continuation of the slide groove 37.

In each of the slides 41 is pivotally mounted a trip member 46 which depends from its pivot, has a thickened lower portion 47, is provided with an upper engaging shoulder 48, and has a rounded edge 49 at its lower end. Each pivoted trip member 46 has journalled therein a roller 50 which travels upon the bottom of the groove 37, and is adapted to engage in either of two concave recesses 51, 51^a, in the bottom of the longitudinal groove 37.

The slides 41 are connected to the slides

36 by means of short bolts 52 and are normally held apart by means of coil springs 53 surrounding the bolts 52 and interposed between the slides 36 and 41.

When either one or both of the slides 41 are moved downwardly the wedge block 27 is raised clear of the cutters 15 and the cutters are free to swing inwardly within the slot 12 of the body member. Upward movement of the wedge block 27 compresses the coil spring 40 so that when the slides 41 are released the wedge block 27 is forced downwardly by the spring 40 into engagement between the inner faces of the cutters 15 forcing the cutters into working position.

The slides 41 are locked in their lowermost position in which the wedge block 27 is held clear of the cutters by holding the pivoted trip members 46 in retracted position, with the rollers 50 engaging in the lower recesses 51, as shown at Fig. 4, while the tool is being inserted into or withdrawn from a well casing, the trips 46 being held in this position by the wall of the casing.

The upper portion of the body member 1 is enclosed by a sleeve 54. The lower end of the sleeve 54 engages a shoulder 55 on the body 1, and also the external shoulder formed by the rabbet 18 on the outer side of the upper end of the cutter shank 16.

A threaded collar 56 is screwed onto the threaded portion 2 of the body member 1 and clamps the sleeve 54 against the shoulder 55. The body member 1 within the sleeve 54 is turned to a slightly smaller diameter except adjacent the ends and center of the sleeve, leaving low peripheral ribs 57 for bearing engagement with the sleeve 54.

In Fig. 2 of the drawing a well casing 58 provided with a driving shoe 59 at its lower end is shown. In Figs. 1 and 2 a pilot or guide member 60 is shown screwed upon the lower nipple 5 of the body member 1.

In Fig. 3 of the drawing a tool holder 61 is shown attached to the lower end of the body member 1. The tool holder 61 may carry a drilling tool or a cleaning tool.

To lower the tool into a well, the slides 41 are pulled down until the trip rollers 50 engage the lower recesses 51 and held in this position until the cutters 15 have entered the upper end of the well casing. As the tool is lowered the trip members 46 are engaged by the wall of the casing and are held in their retracted position with the rollers 50 in the recess 51. The outer face of the thickened portion 47 of the trip members 46 is of sufficient length so that the trip members 46 are prevented from springing out in passing the joints in the well casing. Should a joint be unusually wide the rounded lower corner 49 of the trip will serve to return the trip to its inner position as the trip moves past the joint. As soon as the trip members 46 pass through the driving shoe 59 of the cas-

ing the spring 40 will be released, and will shove the wedge block 27 between the cutters 15, forcing them into working position.

When the cutters 15 are in working position they are rigidly held against inward movement by the block 27, and are rigidly locked against any further outward movement by the engagement of the inner shoulder 17 in the shouldered recess 14, and by engagement of the shoulder 18 against the lower edge of the sleeve 54. When in working position as shown in Fig. 2 of the drawing, the squared upper ends of the shanks 16 of the cutters abut against the square shoulder at the upper ends of the channels 13 in which the shanks 16 are fitted so that the cutters are in solid engagement with the body member 1 and the impacts in operation are transmitted endwise through the cutters so that the danger of breaking the cutters is reduced to a minimum.

When it is desired to withdraw the tool it is simply lifted, which movement causes the cutters to be released and permits the tool to pass freely through the casing. As the tool is lifted the lower edge of the driving shoe 59 engages the shoulders 46 of the pivoted trip members, holding the sleeves 41 against vertical movement, so that they are forced downwardly in the slots 37 until the rollers 50 engage with the lower recesses 51. This movement of the sleeve raises the wedge block 59 and frees the cutters 15.

It sometimes happens that the driving shoe gets out of round. In such case it might be possible that one of the trip members 46 would not be engaged. However, each of the slides 41 has an independent flexible connection with the wedge block 27 so that actuation of either slide will retract the wedge block.

When the tool is being removed from the well casing the trip members 46 may be engaged by a setting clamp 62 before the cutters 15 are removed from the casing. The setting clamp serves to hold the wedge block 27 in retracted position so that the tool can be reinserted in the casing without resetting. Any suitable clamp may be used for this purpose, the clamp 62 shown herein being in the form of a semi-circular bar having set screws 63 engageable with the trip members 46. With the trip members 46 clamped as shown in Fig. 9 of the drawing, the collar 55 may be loosened and the sleeve 54 slipped upwardly until the cutters are released. The cutters may then be replaced and the sleeve 54 clamped in position without disturbing the wedge holding means so that the tool may be immediately reinserted in the well casing.

The spring connection between the slides 36 and 41 together with the upper recess 51^a provides a safety connection for the trip member 46 so that in case one of the trip members should strike against an obstruc-

tion no damage can be done since the trip member will simply force the slide 41 upwardly against the spring 53 until the roller 50 rides into the recess 51^a and the trip member 46 is retracted into the body member. 70

The pilot 60 serves to maintain the tool in proper alignment and prevents the tool from working toward one side or the other of the hole as is apt to occur when the cutters are mounted upon the free end of the tool. 75

Having described my invention, I claim:

1. In a drilling tool, the combination with a body member, of cutters carried by said body member and movable laterally with respect thereto, a wedge block having a tapered lower end engageable with said cutters to force the same outwardly to working position, a spring acting to force the wedge block downwardly, and a plurality of independently movable trip members each engageable with the well casing and adapted to actuate said wedge member in opposition to said spring. 80

2. In a drilling tool, a body member having a cutter receiving slot therein, a cutter mounted for lateral movement in the slot, means carried by the body member and engageable with the cutter to shift the cutter to and rigidly hold the same in working position, the lower end of the cutter being inclined upwardly and inwardly and a spring pressed follower in said slot beneath the cutter engaging the lower end of said cutter in all positions thereof. 90

3. In a drilling tool, a body member, a plurality of cutters carried by said body member and movable laterally with respect thereto, a wedge block having a converging lower end engageable with said cutters, a coil spring for normally holding said wedge block in its lowermost position, slides upon the outer face of said body member, sheaves carried by the body member above the slides, and cables running over said sheaves and connecting each slide to said wedge block. 100

4. In a drilling tool, the combination with a body member carrying collapsible cutters, of an actuating device for said cutters including a longitudinally movable slide mounted upon the face of said body member, said slide having a pivoted trip member 110 normally projecting from the face of said body member, said body member having a recess into which said trip member is adapted to be retracted and in which said trip is adapted to be held by engagement with the well casing to lock said actuating device. 115

5. In a drilling tool, the combination with a body member carrying collapsible cutters, of an actuating device for said cutters including a vertically movable slide mounted upon the face of said body member, said slide consisting of a pair of spring connected parts, one of which is provided with a pivoted trip member which normally projects laterally from the body member, said 125

body member having upper and lower recesses into which said trip member is adapted to be retracted.

6. In a drilling tool, a body member having a cutter receiving slot therein, a cutter mounted for lateral movement in the slot, a slide having a tapered lower end engageable with the cutter to move the cutter to working position, said slide having a flat portion for holding the cutter in working position, and a spring pressed follower in said slot beneath the cutter and engaging the lower end of the cutter in all positions thereof.

7. In a drilling tool, a body member having a cutter receiving slot therein, a pair of pivotally suspended cutters movable from a position entirely within the body member to working position in which the lower cutting edges project laterally from the body, a spring pressed slide movable downwardly into engagement with the cutters to shift the same to cutting position, means engageable with the well casing for retaining the slide in retracted position, and a spring pressed follower engageable with the lower ends of the cutters in all positions thereof.

8. In a drilling tool, a body member having a transverse slot therethrough and longitudinal grooves on opposite sides thereof extending upwardly from the top of the slot, a pair of cutters having enlarged heads fitting in said slot and shanks fitting in said grooves, said heads having shoulders at the sides of the shank and said slot being formed with shoulders against which the shoulders of the cutter bear, means for pivotally sup-

porting the cutters adjacent the upper ends of the slot, said shanks having squared upper ends engageable with the ends of the slots when the cutters are in working position, a sleeve detachably secured to the body member and covering the upper ends of the slots to retain the cutters, and means for moving the cutters to and from working position.

9. In a drilling tool, a body member having a transverse slot therethrough and longitudinal grooves on opposite sides thereof extending upwardly from the slot, said grooves having recesses in the bottoms thereof at their upper ends, said recesses having square shoulders at their lower sides, a pair of cutters having heads fitting within the slot and shanks fitting within the grooves, said shanks having projections on their inner sides projecting into the recesses, said projections having square shoulders engageable with the shoulders at the lower sides of the recesses, said shanks having a pivotal movement about the interengaging shoulders of the recess and projection and said cutters having squared upper ends which abut against the upper ends of the grooves when the cutters are in working position, a sleeve detachably secured to the body member and covering the upper ends of the grooves to retain the cutters, and means for shifting the cutters to and from working position.

In testimony whereof, I hereunto affix my signature.

WILLIAM H. S. MOORE.
